(57) **CLAIM**

The ornamental Design for a tire tread, as shown and
described.

DESCRIPTION

FIG. 1 is a perspective view of a tire tread showing our new
design, it being understood that the pattern repeats uni-
formly throughout the circumference of the tread;

FIG. 2 is a front elevational thereof;

FIG. 3 is a side elevational view thereof;

FIG. 4 is an enlarged fragmentary perspective view; and,
FIG. 5 is a perspective view of an alternative embodiment
thereof.

In the drawings, the broken lines defining the sidewall and
inner bead and the peripheral boundary between the tire
tread and the sidewall are for illustrative purposes only and
form no part of the claimed design.
